Patented Oct. 18, 1921.

UNITED STATES PATENT OFFICE.

EUGENE MOUSSEAUX, OF LE MANS, FRANCE.

STOCK FOR SINGLE-BARRELED OR DOUBLE-BARRELED GUNS.

1,393,812.

Specification of Letters Patent.

Patented Oct. 18, 1921.

Application filed April 5, 1920. Serial No. 371,431.

(GRANTED UNDER THE PROVISIONS OF THE ACT OF MARCH 3, 1921, 41 STAT. L., 1313.)

To all whom it may concern:

Be it known that I, EUGENE MOUSSEAUX, a citizen of France, residing at Le Mans, France, have invented certain new and useful Improvements in Stocks for Single-Barreled or Double-Barreled Guns, of which the following is a specification.

This invention relates to guns, and particularly to the stock of the gun.

10 In order for a gun to be properly aimed, whether the gun is a double barreled gun or a single barreled gun, and whether it is a rifle or a shot gun, it is necessary for the gunner to sight along the upper surface of 15 the gun either between the barrels, where a double barreled gun is used, or over the top of the single barrel.

In order to secure this condition, the axis of all small arms known to me is slightly 20 deviated with reference to the vertical plane passing through this line of sight, but this deviation in all guns known to me is such that the necessary room is not left for the cheek of the gunner between the surface of 25 the stock and this line of sight. Because of the lateral displacement or deviation of the stock, the effect of the recoil, instead of being transmitted directly to the shoulder, follows the axis of the stock created at the 30 moment of rotation and tends to give the muzzle a circular movement.

The general object of my invention is to overcome this difficulty by so shaping the stock as to provide a surface against which 35 the gunner may lay his cheek, such surface being so disposed that the eye of the gunner will be in line with the line of sight, while the recoil is transmitted to the central axis of the posterior portion of the butt and so 40 transmitted properly to the shoulder of the gunner, this surface being of such character as to give a firm and relatively wide support to the cheek of the gunner and eliminating the stop which is found on the upper 45 ridge of all gun stocks known to me, replacing it by a relatively large cheek supporting surface which prevents the gunner from being hurt by the upper stock when the gun recoils, because of being imperfectly held.

Other objects will appear in the course of the following description.

My invention is illustrated in the accompanying drawings, wherein:—

55 Figure 1 is a side elevation of the rear portion of a gun with my improved stock;

Fig. 2 is a top plan of the gun shown in Fig. 1;

Fig. 3 is a section on the line A—A' of Fig. 1;

Fig. 4 is a section on the line B—B' of Fig. 1;

Fig. 5 is a rear end elevation of the butt of the gun;

Fig. 6 is a top plan view of a modified form of stock;

Fig. 7 is a section on the line C—C' of Fig. 6;

Fig. 8 is a section on the line D—D' of Fig. 6.

10 designates the barrels of the gun, which gun is illustrated as a double barreled gun, though my invention is not limited thereto, and 11 the stock of the gun, which is constructed in all respects in the ordinary and conventional manner, except as regards the cross section of the stock.

In Figs. 1 and 2, the line X—Y indicates the line of sight, while the line M'—N' in Figs. 3, 4 and 5 indicates the vertical axial plane of the gun which intersects the line X—Y. This axis of symmetry M'—N', as illustrated in Fig. 5, is medially disposed at the posterior end of the gun butt.

That portion of the stock immediately 85 forward of the rearmost portion of the gun butt, but rearward of the shaft of the stock does not have bi-lateral symmetry, as is illustrated plainly by the sections, Figs. 3 and 4, but the stock is greater in width on 90 one side of this axial plane than on the opposite side. This is done so as to provide a surface, designated 1 in Figs. 3 and 4, which in Figs. 1 to 4, is somewhat convexly curved, against which the gunner may lay his cheek 95 while one eye of the gunner is brought in line with the line of sight X—Y. This curved surface 1 does not terminate at the upper edge of the axial plane, but extends over toward the right of the stock beyond 100 this axial plane, and then the right side face of the stock is slightly hollowed out, as at 2, to afford a good grip for the hand. The rounded face 1 on the line of the cross section A—A' extends downward for about 105 one-half the depth of the stock and on the line of this cross section terminates in the small shoulder 3. The stock on the left side gradually increases in width back to the line of the section D—D', and then gradually decreases in width until it merges into the elliptical section of the posterior end of

the gun butt. The shoulder 3, therefore, gradually merges into the contour on the left side of the stock, while the concave portion 2 gradually gets shallower as it extends rearward.

It will be noticed that the cheek surface 1, with reference to the line of aim, can be such that the eye, when the cheek of the gunner is laid against the gun stock, will be a little above the level of the bottom or groove of the channel between the barrels 1 or a little above the upper surface of the barrel, in the case of single barreled guns, in such a manner that the aim is taken as if the gun were provided with a rear sight.

Another embodiment of my invention is illustrated in Figs. 6, 7 and 8. Here, again, the barrels and stock are of the ordinary type, except as regards the cross sectional 20 form of the stock, but in this embodiment the surface 1 is relatively flat or only very slightly convex, and the angle which this surface makes to the vertical plane M'-N' is less acute than it is in Figs. 3 and 4, and 25 further this inclined surface 1 is broader than it is in Fig. 3.

Furthermore, it will be seen from Fig. 8 that in this embodiment, the greater portion of the material of the stock lies to the right of the medial line M'-N', that a slight shoulder 3' is formed below the surface 1, and that a shoulder on the opposite side of the face is formed by slightly undercutting this side face of the gun, as at 2'. 30 It will likewise be seen from Fig. 6 that the flat surface 1 is relatively narrow at its forward end and gradually becomes wider toward the rear end and more convex, and then becomes narrower and merges into the stock. This particular embodiment is made 40 for gunners who aim with the left eye instead of with the right.

It is to be taken for granted that each gun stock will be so proportioned and have such 45 form as may suit it to the conformation and habits of the individual gunner. Thus, for every gunner the position of the cheek surface 1, degree of its elevation or depression, the degree of its curvature and of its angle, 50 is calculated by taking into account the distance between the cheek and the eye, and so forming this portion of the stock that when the cheek is placed against the surface, the eye will be disposed in alignment with the 55 line of sight, that is a line passing through the foresight, disposed either closer to or farther from the surface of the barrel or the surface of the groove between the barrels, the amount which may be desired.

60 Each individual gunner, where perfection in shooting is desired, is to have the stock made for him, and with special reference to the proper regulation of the gun,

the data for which regulation can be secured by an expert gunsmith by testing the shooting of the gunner with a gun having a stock formed with removable portions corresponding to the protuberances and flattened parts of the gun stock illustrated in the drawings. It will be obvious, therefore, 65 that whatever the conformation of the gunner's head and whatever the action of the gunner in aiming and firing, a stock can be made for him, by which the contact of the stock with the cheek of the gunner automatically brings the aiming eye into the 70 aiming line. The gunner, therefore, has nothing more to do than use the foresight in order to aim properly, because the starting point, that is the aiming eye, must be disposed in the right place at all times.

It is to be understood that I do not wish to be limited to the exact form of the stocks shown in the two above embodiments of my invention, as these are purely illustrative of 85 the general character of my invention, and further it is to be understood that I do not limit myself to the use of a stock wherein the stock is molded or carved from one piece of material, as it is obvious that ordinary 90 stocks may be changed to conform to my invention by gluing or otherwise attaching thereto a new busk or piece which would provide a cheek supporting surface at the proper position and disposed at the proper 95 angle.

I claim:—

1. A gun stock having the vertical axial plane of symmetry of the butt of the stock coincident with the aiming line and having 100 that portion of the stock between the grip and the butt unsymmetrical with respect to the said vertical axial plane, the upper face of said portion being laterally and upwardly inclined to provide a cheek supporting surface, the sides of the stock below said inclined upper surface being reduced in thickness to provide shoulders above the reduced portion.

2. A gun stock having the vertical axial 110 plane of symmetry of the butt of the stock coincident with the aiming line and having that portion of the stock between the grip and the butt unsymmetrical with respect to the said vertical axial plane, the upper face 115 of said portion being laterally and upwardly inclined to provide a cheek supporting surface, the sides of the stock below said inclined upper surface being reduced in thickness to provide shoulders above the reduced portion, said portion of the stock having the inclined face gradually widening rearward and then being reduced and merging into the butt of the stock.

In testimony whereof I affix my signature. 125
EUGENE MOUSSEAU.
